UNITED STATES PATENT OFFICE.

VINCENT BENDIX, OF CHICAGO, ILLINOIS, AND FREDERICK S. ELETT, OF ELMIRA, NEW YORK; SAID ELETT ASSIGNOR TO ECLIPSE MACHINE COMPANY, OF ELMIRA, NEW YORK, A CORPORATION OF NEW YORK.

ENGINE-STARTER.

1,288,476.

Specification of Letters Patent. Patented Dec. 24, 1918.

Application filed August 26, 1916. Serial No. 117,026.

To all whom it may concern:

Be it known that we, VINCENT BENDIX and FREDERICK S. ELETT, citizens of the United States, residing, respectively, at Chicago, 5 Cook county, Illinois, and Elmira, Chemung county, New York; have invented certain new and useful Improvements in Engine-Starters, of which the following is a specification.

10 Our invention relates to that type of engine starter more particularly to the transmission or drive portion thereof, as exemplified in patents heretofore issued to the said Bendix, for instance, Patent No. 1,172,864, 15 issued on February 22, 1916, which starter is characterized by a prime-mover such as an electric motor and a transmission or drive for transmitting the power or motion of the motor by means of a screw shaft device to 20 a member of the engine, such as the fly-wheel thereof. This transmission or drive comprises a screw shaft operated either directly or indirectly by the electric motor and a pinion screw-threaded on such shaft for 25 longitudinal movement thereon and rotary movement therewith. The pinion is weighted or overbalanced by means of an overbalanced disk or the like and the object of our invention is to provide a construction of 30 pinion and weighted disk whereby the disk is securely and effectually fastened to the pinion.

In the drawing, Figure 1 is an elevation of a pinion (partly in section) and a weighted disk embodying my invention, the view being 35 taken looking at the pinion end of the structure; Fig. 2 an elevation thereof looking at the disk end of the structure; Fig. 3 a section on the line 3—3 of Fig. 1 and Fig. 4 a detail section of the weighted disk alone.

Referring to the embodiment of our invention as herein shown, the pinion 1 is provided on its circumference with teeth 1^a extending all the way across the body of the 45 pinion longitudinally thereof, but said teeth at the weight end of the pinion are partially cut away to give a polygonal formation—in the present instance hexagonal. As a result, with a pinion having twelve teeth as herein 50 shown the alternate teeth are cut down practically to their base while the remaining teeth are cut half way down but at an angle corresponding to an inner angle of a hexagon as shown at 1^b.

The weight comprises a disk 2 and a weight proper 2^a, which here constitute a thickened semi-circular marginal flange on the disk. This disk is provided with a central hexagonal opening 2^b which fits accurately the hexagonal reduced end of the pinion, the inner face thereof when applied to the pinion fitting against the shoulder 1^c of the pinion teeth, as shown in Fig. 3.

After the disk is applied to the pinion, the parts are securely fastened against detachment by a swaging operation which consists in distorting the metal of the disk and of the pinion along their hexagonal sides. In practice the swaging is done by the pressure or blow from a chisel, preferably first delivered 65 along the hexagonal sides of the disk, thereby forcing the metal thereat into firm engagement with the hexagonal sides of the pinion. Thereupon a similar swaging operation along the hexagonal sides of the pinion 70 rivets the metal thereon slightly over the hexagonal edges of the disk so that there is no possibility of the disk being removed from the pinion. In practice the pinion teeth are cut back or milled off to an extent 75 slightly greater than the thickness of the disk, with the result that the hexagonal portion of the pinion projects beyond the outer side or surface of the disk, thereby facilitating the swaging operation described. 80

85 We claim:

1. In an engine starter transmission or drive, the combination with a screw shaft, of a driving member screw-threaded thereon for rotary and longitudinal movement 90 and having one end reduced to polygonal form, and a member having a corresponding polygonal opening and fitting upon said reduced end of the driving member.

2. In an engine starter transmission or drive, the combination with a screw shaft, of a driving member screw-threaded thereon for rotary and longitudinal movement and having one end reduced to polygonal 95 form, a disk having a corresponding polygonal opening receiving said reduced end of the member, and means for securing the disk to the said member. 100

3. In an engine starter transmission or drive, the combination of a pinion having one end polygonal, a weighted disk having a corresponding polygonal opening received 105 by said polygonal portion of the pinion, and

means whereby the meeting polygonal sides of the disk and pinion are held in firm engagement.

4. In an engine starter transmission or drive, the combination of a rotatable and longitudinally movable driving member having one end reduced to polygonal form, a disk which is weighted on one side of its axis and has a polygonal opening to receive 10. said reduced end, and means for securing the member and disk together.

5. In an engine starter transmission or drive, the combination of a pinion having one end polygonal and a disk having a polygonal opening corresponding to and fitting upon the polygonal portion of the pinion, the meeting polygonal sides of the pinion and disk being swaged upon each other. 15

6. In an engine starter transmission or drive, the combination of a pinion having teeth extending from end to end thereof, but having such teeth at one end thereof cut away to form a polygonal end, and a disk having a corresponding polygonal opening 20

adapted to fit upon the polygonal end of the pinion.

7. In an engine starter transmission or drive, the combination of a pinion having teeth extending from end to end thereof, but having such teeth at one end thereof cut away to form a polygonal end, and a weighted disk having a corresponding polygonal opening adapted to fit upon the polygonal end of the pinion, the cutaway portion of the pinion projecting beyond the outer surface of the disk, which projecting portion is swaged over to secure the disk to the pinion. 30 35
